UNITED STATES PATENT OFFICE.

GEORGE E. DALBEY, OF EAST BERLIN, AND THOMAS P. HANFORD, OF BERLIN, CONNECTICUT, ASSIGNORS TO THE STANLEY CHEMICAL COMPANY, OF EAST BERLIN, CONNECTICUT, A CORPORATION OF CONNECTICUT.

METHOD OF TREATING MIXTURES CONTAINING ALKALI SALTS OF CERTAIN METALS.

Application filed January 14, 1927. Serial No. 161,238.

This invention relates to a method of treating mixtures containing alkali salts of certain metals.

The particular mixtures in view include 5 sodium arsenate, sodium stannate, sodium antimonate, sodium plumbate, sodium plumbite, sodium zincate and free uncombined caustic alkali. They may include other sodium compounds of metals or of metal oxides and may 10 lack the free caustic alkali, or one or more of the salts mentioned. These mixtures may, of course, be derived from various sources. It is noted, however, that such a mixture results from carrying out the several methods set 15 forth in three copending applications filed of even date herewith, Serial Nos. 161,235, 161,236, 161,237. A mixture of this class also results from carrying out the method set forth in our application filed May 4, 1926, Serial 20 No. 106,726.

It is an object of the invention to provide an economical method of treating such mixtures whereby valuable products may be reclaimed on a commercially practical scale.

With this object in view the invention consists in the method which is hereinafter described then more particularly pointed out in the claims.

A flow-sheet of the process is shown in the drawing.

In carrying out the method of the invention, the mixture is placed in water in such proportion that the water is saturated with any free caustic alkali, usually caustic soda. 35 As this caustic soda is the most readily soluble of the materials involved there is formed a water solution of caustic soda, leaving the other materials out of solution and in suspension.

During this step the sodium antimonate changes to sodium pyro antimonate in the presence of the water.

The water solution of caustic soda is then removed by any suitable mechanical means, 45 and may be used in other chemical reactions, e. g. in the refinement of lead.

The residuum is again placed in water sufficient to dissolve any sodium stannate, sodium zincate and sodium arsenate. While 50 a small amount of sodium plumbate and sodium plumbite may go into solution the major portion remains in suspension with the

sodium pyro antimonate and any insoluble materials, including oxides.

This solution of salts is separated from the 55 undissolved materials by any suitable mechanical means. Its further treatment is later referred to.

Referring now to the further treatment of the undissolved materials, this latter mixture 60 of sodium plumbate, sodium pyro antimonate and any impurities is treated to obtain metallic lead and sodium pyro antimonate. To this end, it is allowed to react with metallic tin, and in carrying out the invention to what is 65 now considered the best advantage, just enough tin is used to reduce the sodium plumbate and sodium plumbite. As a result, the tin is changed to sodium stannate and the sodium plumbate is reduced to metallic lead. 70 During this reaction, with a proper amount of tin, the sodium plumbate and sodium plumbite are substantially entirely reduced to lead before any action takes place on the sodium pyro antimonate. This reaction 75 leaves sodium stannate in solution and out of solution a mixture of sodium pyro antimonate and metallic lead.

The sodium stannate solution is then separated out by suitable mechanical means. 80 Also the sodium pyro antimonate and the metallic lead are separated by mechanical means such as a tabling operation or by ordinary classifiers. The sodium pyro antimonate can be further treated by smelting or otherwise to obtain metallic antimony. 85

Referring back to the solution of metal salts previously removed, this solution is treated to obtain stannic acid. While other products result the stannic acid is considered 90 the most valuable commercially. To this end, the solution is treated with a suitable sulphur compound, e. g. sodium sulphide, to cause precipitation of metal sulphides. As a result of this step the zinc, lead and any 95 other metals forming insoluble compounds in alkaline solution are precipitated out as sulphides. These precipitated materials are removed in any suitable manner, leaving a relatively pure solution of sodium stannate and sodium arsenate. 100

This latter solution is suitably treated with an alkali carbonate, e. g. sodium acid carbonate, to change the sodium stannate to

stannic acid. This may be accomplished if desired by treating the solution with carbon dioxide which combines with the caustic soda to form the sodium carbonate.

5 The stannic acid is precipitated out and may be separated by mechanical means. The sodium arsenate left in solution may be treated to recover arsenic or discarded.

What is claimed is:

10 1. The method of treating mixtures containing sodium-metallic salts to recover valuable products, which comprises dissolving any caustic soda which may be present in the mixture and separating it from the undissolved materials, dissolving the metal salts other than sodium plumbate and plumbite and any sodium pyro antimonate that may be present due to the action of water on sodium antimonate in the original mixture, separating such solution from the undissolved materials, treating the undissolved mixture of sodium plumbate and plumbite and sodium pyro antimonate to obtain metallic lead and sodium pyro antimonate, and treating 25 said solution of metal salts to obtain stannic acid.

2. The method of treating mixtures containing sodium-metallic salts to recover valuable products, which comprises removing, by dissolving in water and mechanical separation of the solution, any caustic soda which may be present and the metal sodium salts other than sodium plumbate or plumbite and any sodium pyro antimonate that may be formed by the action of water on sodium antimonate in the mixture, and treating the undissolved mixture of sodium plumbate or plumbite and sodium pyro antimonate to obtain metallic lead and sodium pyro antimonate.

3. The method of treating mixtures containing sodium-metallic salts to recover valuable products, which comprises removing, by dissolving in water and mechanical separation of the solutions, any caustic soda which may be present and the metal sodium salts other than sodium plumbate or plumbite and any sodium pyro antimonate that may be formed by the action of water on sodium antimonate in the mixture, and treating the undissolved mixture of sodium plumbate or plumbite and sodium pyro antimonate with metallic tin to reduce the sodium plumbate or plumbite to metallic lead.

4. The method of treating mixtures containing sodium-metallic salts to recover valuable products, which comprises removing, by dissolving in water and mechanical separation of the solution, any caustic soda which may be present and the metal sodium salts other than sodium plumbate or plumbite and any sodium pyro antimonate that may be formed by the action of water on sodium antimonate in the mixture, and treating the undissolved mixture of sodium plumbate or

plumbite and sodium pyro antimonate with just sufficient metallic tin to reduce the sodium plumbate to metallic lead without materially affecting the sodium pyro antimonate.

5. The method of treating mixtures containing sodium-metallic salts to recover valuable products, which comprises removing, by dissolving in water and mechanical separation of the solution, any caustic soda which may be present and the metal sodium salts other than sodium plumbate or plumbite and any sodium pyro antimonate which may be formed by the action of water on sodium antimonate in the mixture, separating the soda solution from the solution of salts, and treating the solution of salts to obtain stannic acid.

6. The method of treating mixtures containing sodium-metallic salts, to recover valuable products, which comprises removing, by dissolving in water and mechanical separation of the solutions, any caustic soda which may be present and the metal sodium salts other than sodium plumbate or plumbite and any sodium pyro antimonate which may be formed by the action of water on sodium antimonate in the mixture, separating the soda solution from the solution of salts, treating the solution of salts with a sulphur compound to precipitate sulphides of metals forming insoluble compounds in an alkali solution, removing such precipitated sulphides, and treating the remaining solution with an alkali carbonate to precipitate stannic acid.

7. The method of treating mixtures containing sodium-metallic salts, to recover valuable products, which comprises removing, by dissolving in water and mechanical separation of the solutions, any caustic soda which may be present and the metal sodium salts other than sodium plumbate or plumbite and any sodium pyro antimonate which may be formed by the action of water on sodium antimonate in the solution, separating the soda solution from the solution of salts, treating the solution of salts to obtain a relatively pure solution of sodium stannate and sodium arsenate, and treating said last-named solution with an alkali acid carbonate or carbon dioxide to precipitate stannic acid.

8. The method of treating mixtures containing sodium-metallic salts and free caustic alkali to recover valuable products, which comprises forming a water solution of caustic alkali while maintaining substantially all the other products out of solution, and separating such water solution from the mixture by mechanical means.

9. The method of treating mixtures containing sodium-metallic salts and free caustic alkali to recover valuable products, which comprises forming a water solution of caustic alkali while maintaining substantially all the

other products out of solution, separating such water solution from the mixture by mechanical means, and treating the residuum to obtain stannic acid.

5 10. The method of treating mixtures containing sodium-metallic salts and free caustic alkali to recover valuable products, which comprises forming a water solution of caustic alkali while maintaining substantially all the

other products out of solution, separating such water solution from the mixture by mechanical means, and treating the residuum to obtain metallic lead. 10

In testimony whereof, we have hereunto set our hands.
